(57) **CLAIM**

The ornamental design for a round shaped refrigerator and double display, as shown and described.

DESCRIPTION

FIG. 1 is a top plan view of a round shaped refrigerator and double display showing my new design;

FIG. 2 is a front elevational view; the opposite side being the mirror image of that shown;

FIG. 3 is a right hand side elevational view thereof; the opposite side being the mirror image of that shown;

FIG. 4 is a perspective view thereof; the opposite side being the mirror image of that shown;

FIG. 5 is a top plan view of a second embodiment of a round shaped refrigerator and double display embodying of my new design;

FIG. 6 is a front elevational view; the opposite side being the mirror image of that shown;

FIG. 7 is a right hand side elevational view thereof; the opposite side being the mirror image of that shown; and,

FIG. 8 is a perspective view thereof; the opposite side being the mirror image of that shown.
